COLLAPSIBLE BRIDGE TABLE

William S. Ritchie, Winnipeg, Manitoba, Canada

Application December 27, 1934, Serial No. 759,420
In Canada December 3, 1934

3 Claims. (Cl. 311—85)

My invention relates to improvements in collapsible bridge tables and an object of the invention is to provide a collapsible bridge table in which the four legs may be extended in one simple movement of a lever or handle beneath the table.

A further object of the invention is to provide a collapsible bridge table of this character which when extended is rigid and serviceable.

10 A further object of my invention is to provide a bridge table of this character, the legs of which when collapsed against the under side of the table top, will stay rigidly in that position until extended.

15 A further object of my invention is to provide a collapsible bridge table of this character which is economical to manufacture and will not become out of order.

With the foregoing more important objects in view and such other minor objects as may appear as the specification proceeds, my device consists in the arrangement and construction of parts, all as hereinafter more particularly described, reference being had to the accompanying drawings, in which:—

Fig. 1 is a side elevation of my table with the legs broken.

Fig. 2 is a plan view of the under side of my table with the legs extended.

30 Fig. 3 is a plan view of the under side of my table with the legs folded into the collapsed position.

Fig. 4 is a section on the line 4—4 Fig. 2.

Fig. 5 is a similar section to Fig. 4 but with the 35 legs partially unfolded.

Fig. 6 is an enlarged detail showing my spring clip from the side.

Fig. 7 is a plan view of my spring clip.

Fig. 8 is a side view of my spring clip.

40 In the drawings like characters of reference indicate corresponding parts in the different figures.

While I am aware of the existence of various types of collapsible bridge tables, extendable by 45 means of levers, etc., their apparent disadvantage is that they are not sufficiently rigid to be serviceable and are frequently of a complicated nature and expensive to manufacture. My invention seeks to overcome these objections.

50 Adjacent the edges of the under side 1 of the table top 2, I provide a wooden boxing 3. Adjacent each corner of this boxing are pairs of legs 4 and 5. Two lengthwise extending members 6 extend across the under side of the table centrally thereof being bolted to the sides of the box-

ing. Journalled in orifices 7 in these cross members is a double crank 8 and extending from this double crank, is a handle 9.

Crank arms 10 and 11 are freely mounted upon each of the crank portions 12 and 13 respectively, the opposite ends of the crank arms being connected to cranks 14 and 15. The cranks 14 and 15 are formed in a pair of rods 16 and 17, the ends of which are rigidly secured to the upper ends of the legs 4 and 5. The rods 16 and 17 are firmly mounted for rotational movement in bearings 18 secured to the under side of the table surface.

Projecting members 19 in the form of springs are mounted upon one of the members 6. These 15 may be of any desired form and are for the purpose of securing the handle 9 parallel with the member 6 when the legs are extended or collapsed.

I would here mention that further cross members 20 are provided for the purpose of imparting further rigidity to the whole structure and for providing additional bearings for the cranks 16 and 17.

Assuming the table to be collapsed as shown in 25 Figure 3, it is merely necessary to grasp the handle 9 and swing it through an arc of 180° in order to extend the legs of the table as shown in Figure 2. While this action is taking place, the cranks 12 and 13 will reverse their positions 30 which will cause the crank arms 10 and 11 to push the cranks 14 and 15 from their positions parallel with the under side of the table surface into the perpendicular thereby causing the legs to extend perpendicularly to the table surface. 35

In this way, it may be seen that I have provided mechanism for extending and collapsing the legs of a small table such as a card table, very simply and efficiently and have devised a construction which is economical to manufacture 40 and that cannot become out of order.

Since various modifications can be made in the above invention, and many apparently widely different embodiments of same, made within the scope of the claims without departing from the 45 spirit and scope thereof, it is intended that all matter contained in the accompanying specification shall be interpreted as illustrative only and not in a limiting sense and I desire only such limitations placed thereon as are specifically expressed in the accompanying claims.

What I claim as my invention is:—

1. A collapsible table comprising, a combination with a table surface and swingable legs attached thereto and lying therebeneath, rotatable 55

- rods extending between pairs of said legs, crank portions upon said rods, further cranking means beneath said table, a lever attached to said further cranking means, crank arms extending between said further cranking means and said crank portions, said lever being manually operable to swing said legs into extended or closed position.
2. A collapsible table comprising, in combination with a table surface and swingable legs attached thereto and lying therebeneath, a rod rigidly attached adjacent the upper ends of pairs of said legs and extending therethrough, an angulated crank portion upon each of said rods, bearings beneath said table and double and contiguous opposed cranks journaled in said bearing, a lever arm extending from said cranks, crank arms connecting said contiguous opposed cranks with said angulated cranking portion,

said lever being manually operable to rotate said cranks and swing said legs into extended or closed position.

3. A collapsible table comprising, in combination with a table surface and swingable legs attached thereto and lying therebeneath, rods extending between, through and rigidly attached to pairs of said legs adjacent the upper ends thereof, a portion of said rods being angulated to form cranking portions, a bearing beneath said table, a rod bent angularly to form a pair of contiguous opposed cranks, the end of said rod being bent to form a lever arm, a pair of crank arms extending between said contiguous cranks and said cranking portions, said lever being manually operable to swing said legs into extended or closed position.

WILLIAM S. RITCHIE.
